UNITED STATES PATENT OFFICE.

CHESTER M. LEE, OF WESLEY, IOWA.

COLLAPSIBLE CRATE.

1,238,028.

Specification of Letters Patent. Patented Aug. 21, 1917.

Application filed October 8, 1915. Serial No. 54,806.

To all whom it may concern:

Be it known that I, CHESTER M. LEE, a citizen of the United States, residing at Wesley, in the county of Kossuth and State of Iowa, have invented new and useful Improvements in Collapsible Crates, of which the following is a specification.

This invention relates to a crate of the collapsible type which when collapsed requires a small amount of space for shipment or storage.

The primary object of the invention is to provide a bottom section having recesses therein adapted to receive spaced standards on the side sections of the crate and prevent the outward movement of the same when said sections are in a vertical position, and also to provide end sections which cooperate with recesses in the bottom section to prevent the inward movement of the side sections of the crate when the same is assembled.

Another object of the invention is to provide a removable cover for the crate which maintains the end sections of the crate engaged with the side sections thereof in such a manner as to prevent undue strain being imposed upon the hinge connections of the side sections by the contents of the crate, and also to prevent inward movement of the end section when the crate is assembled.

A still further object of the invention is to provide the crate with novel clamping elements which may be engaged with the end sections of the crate when the same is assembled, or engaged with the bottom section of the crate in such a manner as to insure the various sections of the crate remaining in a folded condition when the crate is collapsed.

With these and other objects in view the invention consists in the novel combination and arrangement of parts which will be hereinafter more fully described and particularly pointed out in the claim.

The preferred embodiment of the invention has been illustrated in the accompanying drawings, although no restriction is necessarily made to the precise details of construction therein shown, as changes, alterations and modifications within the scope of the claim may be resorted to when desired.

In the drawings:—

Figure 1 is a perspective view of the improved crate constructed in accordance with the invention, the same being shown in an assembled condition. 55

Fig. 2 is a perspective view showing the cover section removed, and the end sections 60 and one side section folded within the bottom section.

Fig. 3 is a top plan view of the crate in a folded condition with the cover section removed. 65

Fig. 4 is a section on the line 4—4 of Fig. 1, and

Fig. 5 is a bottom plan view of the cover section.

Like characters of reference denote corresponding parts throughout the several views in the drawings. 70

The numeral 1 designates the crate as a whole which comprises a bottom section, side and end sections hingedly connected 75 with the bottom section and a removable cover section.

The bottom section 2 which is rectangular in shape comprises side walls 3 and end walls 4, the side walls 3 being recessed, as indicated at 5, while the end walls which form a wall of the recesses at the ends of the side walls have secured thereto a cleat 6, the ends of which are in spaced relation with the side walls 3 at the opposite ends of the 85 crate for a purpose which will be hereinafter described.

The side sections 7 each comprising spaced standards 8 and spaced longitudinally extending strips 9 which are connected with 90 the standards in any suitable manner. Each of the standards 8 have one end thereof hinged to the side walls 3 of the bottom section, as indicated at 10. When the side sections 7 are moved to a vertical position 95 the hinged ends of the standards are disposed upon the bottom walls of the recesses 5 in the side walls 3 and thereby prevent outward and lateral movement of the side sections. 100

A standard 8 upon each side section 7 intermediate the ends of said section, is provided with a groove 11 in which is positioned a removable partition 12 when the crate is assembled, and it is desired to divide the crate into two compartments. 105

Each of the end sections 13 like the side section 7 are identical in construction and comprise spaced standards 14 to which are nailed spaced cross strips 15 in such a manner as to cause the standards on the end sections when the crate is assembled to register with the standards on the ends of the side sections. The bottom ends of the standards 14 are disposed between the side walls 3 of the bottom section and the ends of the cleats 6 to which the ends of the standards 14 on the end sections are pivoted to permit swinging movement of the end sections in an inward direction.

The cover section 16 of the crate comprises spaced longitudinally extending strips 17, spaced transversely extending strips 18 and depending side and end walls 19 and 20. Secured to a plurality of the longitudinally extending strips 17 on opposite sides of the cover 16 and in spaced relation with the end walls 20 are cleats 21, which contact with the standards 14 and prevent inward movement of the end sections 13 when the crate is assembled.

Secured to a transverse strip 18 intermediate the ends of the cover, is a spring latch 22 which normally serves to hold a pair of sliding doors 23 in the cover 16 in closed position, each of said doors comprising a transverse strip 24 having the opposite ends thereof grooved, as at 25 to receive a portion of the longitudinally extending strips 17 between which said transverse portion of the door 23 is located, and a longitudinally extending strip 25' slidably beneath the transversely extending strip 18 at an end of the cover section.

Located at opposite ends of the end walls 20 of the cover section 16 are locking members 27 formed from suitable resilient material and each comprising a vertical portion movably connected with the end walls 20 and angularly extending arms 29 and 30, the arms 30 being adapted to be positioned beneath a strip on the end section 13 when the crate is assembled, while the arms 29 are frictionally maintained beneath latches 31 on the end walls 20 of the cover section.

It will of course be understood that when the cover is in the above mentioned position the crate is assembled and that the cleats 21 on the underside of the strip 17 are in contact with the upper portion of the standards 14 which prevent inward movement of the end sections of the crate, while the side walls 19 of the cover section 16 prevent undue strain being imposed upon the hinge connection of the side walls by the contents of the crate, and thereby providing a crate construction which is extremely stable when assembled.

It is, of course, to be understood that the manner of assembling the crate is directly

reverse to the manner of collapsing the same so that the following description which describes the collapsing of the crate will enable a person using the crate to assemble the same by reversing the operation required to collapse the crate.

When the crate is to be collapsed the arms 30 of the locking members 27 are moved from beneath the top strips on the end sections and the cover removed from the crate. If the partition 12 has been used to divide the interior of the crate into two compartments the same is withdrawn and placed upon the bottom of the crate. The standards on the end sections which are now free from frictional engagement with the standards on the ends of the side sections are now moved inwardly until the cleats 14 rest upon the bottom of the bottom frame section. The side sections are now folded upon the end sections and within the bottom section.

Each end wall 4 of the bottom section is provided near each end thereof with a longitudinally extending slot 32 which communicates with the interior of the bottom frame section adjacent the upper edge of the cleat 6. When the cover section 16 is disposed upon the bottom frame section and the end and side sections are disposed therein the locking members 27 have the arms 30 thereof inserted within said slots with the arms 29 frictionally contacting with the underside of the keepers 31, thus providing means for securing the cover section to the bottom frame section and insuring the crate remaining in a collapsed condition.

It will be noted with reference to Fig. 4 of the drawing that the end walls 4 and side walls 3 prevent the outward movement of the end and side sections of the crate when in a vertical position and that the cleats on the cover section prevent inward movement of the end sections of the crate and cause the standards 14 to register with and abut against the standards 8 on the side sections 7 when the crate is assembled.

From the foregoing description taken in connection with the accompanying drawings, it is at once apparent that a crate construction has been provided which is inexpensive of manufacture, simple in construction and durable in use.

Having thus described the invention, what I claim is:

A collapsible crate having side and end walls and a bottom to the sides of which the side walls are connected to fold inwardly of the crate, a cleat at each end of said bottom extending transversely thereof and having its ends spaced from the side walls of the crate, end bars on the end walls of the crate pivotally connected at their lower ends with the ends of said cleats, a cover having strips upon the underside thereof to engage

with the end bars on the end walls of the
crate and prevent inward movement of said
end walls when in vertical position, strips at
the ends of said bottom connected with said
5 cleats and engageable with said end bars to
prevent outward movement of the end walls
of the crate when in vertical position, said
strips having slots therein, and means for

locking said cover to said bottom adapted
to extend within said slots. 10

In testimony whereof I affix my signature
in presence of two witnesses.

CHESTER M. LEE.
